UNITED STATES PATENT OFFICE.

ALBERT E. MULLEN, OF NEW YORK, N. Y.

CONTAINER.

Application filed May 1, 1928. Serial No. 274,233.

My invention relates to containers and refers particularly to containers adapted for toilet requisites.

The device of my invention is directed to a container for a plurality of toilet articles, such as powder compacts, rouges and other articles which are of easy access.

Another object of my invention is a device in which a mirror is exposed for use when any of the toilet requisites is exposed for use.

Another object of my invention is a container for a plurality of toilet requisites comprising a plurality of sections, or elements, independent of each and without hinged fastening means between them.

Another object of my invention is a plurality of compact, or similar, containers, movably connected to each other by means of a cord.

Another object of my invention is a compact, or similar container, the construction of which presents a novel, artistic and attractive appearance.

The above mentioned, and other, novel and useful features of my device will be evident upon a consideration of my specification and its accompanying drawings.

In the accompanying drawings illustrating one form of the device of my invention similar parts are designated by similar numerals.

Figure 1 is a perspective view of one form of my device in closed position.

Figure 2 is a vertical section of the device of Figure 1 with several sections in non-abutting positions.

Figure 3 is a section through the line 3—3 of Figure 2.

Figure 4 is a section through the line 4—4 of Figure 3.

Figure 5 is a section through the line 5—5 of Figure 2.

Figure 6 is a section through the line 6—6 of Figure 5.

Figure 7 is a section through the line 7—7 of Figure 5.

Figure 8 is a section through the line 8—8 of Figure 2.

Figure 9 is a section through the line 9—9 of Figure 8.

Figure 10 is a perspective view of the device of Figure 1 with the contents of the middle section exposed for use.

The particular form of the device of my invention shown in the accompanying drawings comprises a plurality of sections A, B and C made of any suitable material, but I

prefer to employ a phenolic condensation product as it allows of artistic color effects and is easily worked into the desired form of construction. In the particular form illustrated the sections A, B and C are of parallelogram shape, the upper surface A being convex for purposes of attractiveness. 60

The inner face of section A is recessed and carries a mirror 11. Two openings 12, 12, 65 pass through opposite corner portions of section A, the lower portion of each opening being of somewhat larger diameter than the upper portion.

The upper face of section B has the annular recess 13. A compact 14 and a powder puff 15 are positioned within recess 13. Two hollow cord guides 16, 16, pass through the openings in opposite corner portions and extend beyond the two faces of section B. 70

The under face of section B has two recesses 17 and 18. Within the recess 17 is a powder compact 19 and a powder puff 20. Within the recess 18 is a rouge container 21 having the hinged cover 22 and containing 75 the rouge 23.

The section C has a recess carrying the mirror 24. Two openings 25, 25, pass through opposite corner portions of section C, the upper portion of each opening being 80 of somewhat larger diameter than the lower portion.

A cord 26 passes through the corresponding openings in sections A, B and C, has a knot 27 at each lower extremity of the openings 25, 25, 90 of section C and carries a tassel 28.

The cord 26 also passes through the two openings 29, 29, of the locking member 30.

The operation of the device is as follows:—

When the device is not in use, the locking member 30 is moved downwardly into the position shown in Figure 1, the frictional contact between the cord 26 and the inner faces and edges of the openings 29, 29, preventing the device from being opened. 95

When it is desired to use the compact 14, the locking member 30 is moved upwardly along the cord 26, and section A raised from section B and inclined rearwardly as shown in Figure 10. 100

When it is desired to use the compact 19 or the rouge 23, the device is inverted and section C is raised and inclined rearwardly.

It is to be noted that when access is obtainable to any of the compacts or to the rouge, a 110 mirror is presented for use.

It is evident that the number of recesses

within the sections may be varied from those shown without going beyond the limits of my invention.

It will thus be seen that my invention comprises a device containing a plurality of compact, or toilet articles, any one of which is accessible without disturbing the others and in which a mirror is thus always exposed for use, these results being accomplished by a plurality of independent sections, all slidable along a cord, the cord acting also as a means for carrying the device.

I do not limit myself to the particular size, shape, number, arrangement or material of parts as shown and described, as these are given simply as a means for clearly describing my invention.

What I claim is:—

1. In a toilet requisite container, in combination, a plurality of independent superimposed sections having aligned openings therethrough, a mirror carried by the inner face of the upper section, a section abutting upon the upper section and having recesses within both faces thereof, a lower section abutting upon the last mentioned section and having a mirror carried by its abutting face and a cord passing through said aligned openings.

2. In a toilet requisite container, in combination, a plurality of independent superimposed sections having aligned openings therethrough, a mirror carried by the inner face of the upper section, a section abutting upon the upper section and having recesses within both faces thereof, a lower section abutting upon the last mentioned section and having a mirror carried by its abutting face and a cord passing through said aligned openings maintaining the said sections in abutment when the device is suspended by said cord.

3. In a toilet requisite container, in combination, a plurality of independent superimposed sections having aligned openings therethrough, a mirror carried by the inner face of the upper section, a section abutting upon the upper section and having recesses within both faces thereof, a lower section abutting upon the last mentioned section and having a mirror carried by its abutting face, a cord passing through said aligned openings and a locking means carried by said cord.

4. In a toilet requisite container, in combination, a plurality of independent superimposed sections having aligned openings therethrough, a mirror carried by the inner face of the upper section, a section abutting upon the upper section and having recesses within both faces thereof, a lower section abutting upon the last mentioned section and having a mirror carried by its abutting face, a cord passing through said aligned openings main-

taining the said sections in abutment when the device is suspended by said cord and a locking means carried by said cord.

5. In a toilet requisite container, in combination, a plurality of independent superimposed sections having aligned openings therethrough, a cord guide passing through each opening of the inner section, a mirror carried by the inner face of the upper section, a section abutting upon the upper section and having recesses within both faces thereof, a lower section abutting upon the last mentioned section and having a mirror carried by its abutting face and a cord passing through said aligned openings.

6. In a toilet requisite container, in combination, a plurality of independent superimposed sections having aligned openings therethrough, a cord guide passing through each opening of the inner section, a mirror carried by the inner face of the upper section, a section abutting upon the upper section and having recesses within both faces thereof, a lower section abutting upon the last mentioned section and having a mirror carried by its abutting face, and a cord passing through said aligned openings maintaining the said sections in abutment when the device is suspended by said cord.

7. In a toilet requisite container, in combination, a plurality of independent superimposed sections having aligned openings therethrough, a cord guide passing through each opening of the inner section, a mirror carried by the inner face of the upper section, a section abutting upon the upper section and having recesses within both faces thereof, a lower section abutting upon the last mentioned section and having a mirror carried by its abutting face, a cord passing through said aligned openings and a locking means carried by said cord.

8. In a toilet requisite container, in combination, a plurality of independent superimposed sections having aligned openings therethrough, a cord guide passing through each opening of the inner section, a mirror carried by the inner face of the upper section, a section abutting upon the upper section and having recesses within both faces thereof, a lower section abutting upon the last mentioned section and having a mirror carried by its abutting face, a cord passing through said aligned openings maintaining the said sections in abutment when the device is suspended by said cord and a locking means carried by said cord.

Signed at New York city, in the county of New York and State of New York, this 28th day of April, 1928.

ALBERT E. MULLEN.
